UNITED STATES PATENT OFFICE.

FREDERICK W. JUDD, OF CLEVELAND, OHIO, ASSIGNOR TO THE WROUGHT IRON RANGE COMPANY, OF ST. LOUIS, MISSOURI.

DESIGN FOR A RANGE-RESERVOIR TOP PLATE.

SPECIFICATION forming part of Design No. 33,261, dated September 25, 1900.

Application filed February 28, 1900. Serial No. 6,838. Term of patent 14 years.

To all whom it may concern:

Be it known that I, FREDERICK W. JUDD, a citizen of the United States, and a resident of Cleveland, county of Cuyahoga, and State of Ohio, have invented and produced a new and original Design for Top Plates for Range-Reservoirs, of which the following is a specification, reference being had to the accompanying drawing, forming a part thereof.

10 The figure represents a perspective view of a top plate for a water-reservoir used as a range attachment, showing my new design.

As shown in the drawing, the leading feature of the design consists in the rounded or 15 semicircular ends of the plate having a marginal groove a , paralleling the edge of the plate and a lid a' , located at or near one end, having its outer rounded edge a^2 and two contiguous edges a^3 also parallel with the adjacent edges of the plate, as shown, said lid 20 being provided with two projected ears a^4 ,

which lie in depressions formed upon the inner raised boundary of the groove a and communicating with said groove a and the opening covered by said lid. Said ears are 25 located equidistantly from a median line passing through the middle of the lid-surface and the middle of the plate-surface and have their respective axes coincident with radii of the circle of which the circular edge of the 30 lid forms part of the circumference.

Having described my invention, what I claim as new, and desire to secure by Letters Patent, is—

The design for a range-reservoir top plate, 35 as herein shown and described.

Signed by me this 2d day of February, 1900.

FREDERICK W. JUDD.
